UNITED STATES PATENT OFFICE

112,292

DESIGN FOR A PLAYING CARD

Owen S. Ottewell, St. Paul, Minn., assignor to Brown & Bigelow, St. Paul, Minn., a corporation of Minnesota

Application December 15, 1937, Serial No. 73,638

Term of patent 3½ years

To all whom it may concern:

Be it known that I, Owen S. Ottewell, a citizen of the United States, residing at St. Paul, county of Ramsey, and State of Minnesota, have invented a new, original, and ornamental Design for a Playing Card, of which the following is a specificcation, reference being had to the accompanying drawing, forming part thereof.

The figure is a back view of a playing card,
the face thereof being conventional, showing my new design.

I claim:

The ornamental design for a playing card, as shown and described.

OWEN S. OTTEWELL.
